Primary Examiner — Robert M. Spear*Assistant Examiner* — Darcey E Heflin(74) *Attorney, Agent, or Firm* — Barnes & Thornburg LLP; Mark J. Nahnsen(57) **CLAIM**

The ornamental design for a de-icer scraper cap, as shown and described.

DESCRIPTION

FIG. 1 is a perspective view taken from the front and left side of a de-icer scraper cap in accordance with my new design;

FIG. 2 is a perspective view taken from the rear and right side of the de-icer scraper cap shown in FIG. 1;

FIG. 3 is a front elevational view of the de-icer scraper cap shown in FIG. 1;

FIG. 4 is a rear elevational view thereof;

FIG. 5 is a right-side elevational view thereof;

FIG. 6 is a left-side elevational view thereof;

FIG. 7 is a top view thereof; and,

FIG. 8 is a bottom view thereof.

The claim is directed to the shaded surfaces only.

The broken lines depict portions of the de-icer scraper cap that form no part of the claimed design.
